UNITED STATES PATENT OFFICE.

CHARLES F. RANDALL, OF BOSTON, MASSACHUSETTS, ASSIGNOR TO MILLS WOVEN CARTRIDGE BELT COMPANY, OF WORCESTER, MASSACHUSETTS, A CORPORATION OF MASSACHUSETTS.

ADJUSTABLE STRAP FOR GUN-SLINGS AND THE LIKE.

1,186,496.

Specification of Letters Patent.

Patented June 6, 1916.

Application filed September 14, 1915. Serial No. 50,709.

To all whom it may concern:

Be it known that I, CHARLES F. RANDALL, a citizen of the United States, residing at Boston, in the county of Suffolk, State of 5 Massachusetts, have invented a certain new and useful Improvement in Adjustable Straps for Gun-Slings and the like, of which the following is a specification, reference being had therein to the accompanying 10 drawings.

The invention has relation to adjustable straps of the differential class. In general, an article of such class heretofore has comprised a strip of material, for instance webbing or leather, that is doubled back upon itself lengthwise to produce opposite terminal return bends, with a link that is attached to a return portion of one of such bends engaged, after the fashion in which a pulley 15 engages in the bend or bight of a rope, with an intermediate return bend formed in a return portion of the opposing terminal return-bend. The assembled or made-up strap 20 in its entirety constitutes a closed loop and 25 has the characteristic that its effective length between one terminal return-bend and the other may be increased or reduced at will through the differential action accompanying a shift of the intermediate return-bend toward one terminal return-bend 30 or the other as the case may be.

The invention is applicable in the case of adjustable straps used as suspensory or connector straps for a variety of purposes, and 35 it consists in an improved adjustable strap of the differential class comprising a novel combination and arrangement of flexible strip, links, etc.

The drawings show an embodiment of the 40 invention in a gun-sling having the typical features of the class of straps referred to, but distinctively characterized, and possessed of its own special features.

In the said drawings, Figures 1 and 2 45 represent such sling applied to a rifle. In Fig. 1 the sling is represented in shortened and tight condition, and in Fig. 2 it is represented in extended and loose condition. Fig. 3 is an edge view of the strap in its 50 shortened state, detached and on a larger scale than Figs. 1 and 2, with portions broken out in order to shorten the view. Fig. 4 is a face view of the strap as shown in Fig. 3. Fig. 5 is an edge view of the

strap in extended state and bent or curved, 55 also with portions broken out.

Referring to the drawings:—In conformity with the invention, the two terminal return-bends, 1, 2, are produced in the respective end-portions of the strip by doubling each end-portion back upon itself, and there are two intermediate return-bends, 3, 4, produced by doubling the intermediate portion of the strip back and forth upon itself, first in one direction to produce bend 65 3 facing terminal bend 1, and then in the other direction to produce bend 4 facing terminal bend 2. The doubled-back extremities, each constituting one side of a terminal return-bend, are engaged with the intermediate return-bends so that thereby the two intermediate return-bends are extended, respectively, in opposite directions. In this instance the engagement is effected detachably by means of snap-hooks 5, 6, taking 70 hold of links 7, 8, applied to such return-bends. Thus, the extremity 9 which constitutes one side of the return-bend 1 is provided with a snap-hook 5 that takes hold of link 7 applied to one intermediate return-bend, 3, and the opposite extremity, 10, also 75 is provided with a snap-hook 6 that takes hold of link 8 applied to the other intermediate return-bend, 4. This detachable engagement of the two extremities of the 80 strip facilitates the assembling or making-up of the adjustable strap, and also facilitates the operations of applying the strap in making use of the same, and of disconnecting or removing it. However, while detachability usually is desirable it is not essential in all cases.

Preferably, the engagement in the case of one extremity and the corresponding intermediate return-bend is of a character to permit the strip to slip or render lengthwise at such bend, as required for alteration of the effective length of the strap, while the engagement between the other extremity and the corresponding intermediate return-bend is non-slipping, so as to reduce the amount of manipulation required in applying and adjusting the strap. In the illustrated embodiment the link 8 is a simple link, around one bar of which the intermediate return-bend 4 is looped, so that the strip may readily be drawn lengthwise through the opening of such link, in adjust-

ing the effective length of the strap. The link 7 is a double link with two openings and a middle bar around which the intermediate return-bend is looped. Snap-hook 5 is engaged with one outside cross-bar of the link 7, and the effect of strain is to cause the said link to tend to assume a position in which the middle bar is in the line of strain. This causes the other outside cross-bar thereof to bear against an adjoining portion of the strip, thereby bending the return-bend bodily more or less around the middle bar, producing friction which opposes movement of the strip lengthwise through the link.

In making use of the strap the respective terminal return-bends are conjoined with suitable connector-means, according to the purpose which the strap is designed to subserve and the place and manner of application. For instance, in the present embodiment the upper terminal return-bend, 1, is looped through the upper gun-swivel 11, Figs. 1 and 2, such gun-swivel constituting in this case a connector-means for such terminal return-bend, and the lower terminal return-bend, 2, is looped through the lower gun-swivel, 12, which constitutes a connector-means for such terminal return-bend. The connector-means may be combined, engaged, or formed with the desired object or objects as here shown, or may be links, hooks, eyes, or other engaging devices that are attached or applied to the terminal return-bends, and in the latter case they may be adapted to engage with the desired objects, or with each other, as may be necessary or desired. In case the connector-devices 11 and 12 are not themselves parts of the adjustable strap, taking the latter as a whole, I preferably make the engagement of the respective end-portions of the strip with the intermediate return-bends 3 and 4 of a readily disconnectible and re-connectible character, as herein, so as to facilitate connection of the terminal return-bends with the connector-devices, as well as disconnection therefrom, and thereby provide for convenient application and removal of the strap in making use of the same.

The effective length of the strap is determined by the proportion of the length of the strip that is taken up by and between the two intermediate bends, and may be varied at will by making adjustment of the intermediate return-bends toward or from each other.

Assuming the strap to be applied as in Fig. 1, and to be in shortened and taut condition as in such figure, its effective length may be made greater by manipulation which will cause intermediate return-bend 3 to shift from its position in Fig. 1 toward the terminal return-bend 2. This shift may be caused to occur by taking hold of the link

7 and moving it bodily toward the said terminal return-bend, and such movement may if desired be continued until the two links 7 and 8 come together. It will be observed that in Figs. 2 and 5 in which such links are close together the length of the extended strap is practically the maximum attainable with a given length of material doubled upon itself. The same shift may be effected by taking hold of one or both of the portions of intermediate return-bend 3 below link 7 and pulling the same toward terminal return-bend 2, or by taking hold of the portion extending from intermediate return-bend 4 toward terminal return-bend 1 and pulling upon the said portion toward the latter terminal return-bend. When the effective length of the strap exceeds the minimum, the said effective length will be reduced, and the strap may be tightened, by pulling in the reverse direction to that before mentioned in the case of the link 7 or of the respective portions of the strip.

It will be observed that the illustrated construction permits the strap to be disconnected quickly from the gun and opened out to the full length of the strip, thereby enabling the strip to be used in such condition whenever required.

The invention is not necessarily restricted to the use of a flat strip of material.

The link 7 has been referred to as providing for non-slipping engagement between extremity 9 of the strip and intermediate return-bend 3. Its construction, however, does not preclude it from being shifted at will along the strip to the required point thereon.

I claim as my invention:

1. An adjustable strap of the differential class, comprising a strip having two terminal return-bends produced by doubling each end-portion back upon itself, and also having two intermediate return-bends produced by doubling the intermediate portion of the strip back and forth upon itself, first in one direction to produce one of the latter return-bends and then in the other to produce the other thereof, with its extremities respectively engaged with the respective intermediate return-bends, said intermediate return-bends adjustable to vary the amount of strip taken up thereby, and the effective length of the strap.

2. An adjustable strap of the differential class, comprising a strip having two terminal return-bends produced by doubling each end-portion back upon itself, and also having two intermediate return-bends produced by doubling the intermediate portion of the strip back and forth upon itself, first in one direction to produce one of the latter return-bends and then in the other to produce the other thereof, with its extremities respectively engaged detachably with the respec-

tive intermediate return-bends, said intermediate return-bends adjustable to vary the amount of strip taken up thereby, and the effective length of the strap.

5 3. An adjustable strap of the differential class, comprising a strip having two terminal return-bends produced by doubling each end-portion back upon itself, and also having two intermediate return-bends produced 10 by doubling the intermediate portion of the strip back and forth upon itself, first in one direction to produce one of the latter return-bends and then in the other to produce the other thereof, and links with which, respectively, the said intermediate return-bends 15 respectively are engaged, and with the extremities of the said strip respectively engaged with the said links.

4. An adjustable strap of the differential 20 class, comprising a strip having two terminal return-bends produced by doubling each end-portion back upon itself, and also having two intermediate return-bends produced by doubling the intermediate portion of the 25 strip back and forth upon itself, first in one direction to produce one of the latter return-bends and then in the other to produce the other thereof, and links with which, respectively, the said intermediate return-bends 30 respectively are engaged detachably, and with the extremities of the said strip respectively engaged with the said links.

5. An adjustable strap of the differential class, comprising a strip having two termi-

nal return-bends produced by doubling each 35 end-portion back upon itself, and also having two intermediate return-bends produced by doubling the intermediate portion of the strip back and forth upon itself, first in one direction to produce one of the latter return-bends and then in the other to produce the other thereof, with a slipping link engaged 40 with one of said intermediate return-bends and a non-slipping link engaged with the other thereof, and with the extremities of 45 said strip respectively engaged with the said links.

6. An adjustable strap of the differential class, comprising a strip having two terminal return-bends produced by doubling each 50 end-portion back upon itself, and also having two intermediate return-bends produced by doubling the intermediate portion of the strip back and forth upon itself, first in one direction to produce one of the latter return-bends and then in the other to produce the other thereof, with a slipping link engaged 55 with one of said intermediate return-bends and a non-slipping link engaged with the other thereof, and with the extremities of 60 said strip respectively engaged detachably with the said links.

In testimony whereof I affix my signature in presence of two witnesses.

CHARLES F. RANDALL.
